LIQUID FUEL BURNER

Ralph W. De Lancey, Meriden, Conn., assignor to
 The Miller Company, Meriden, Conn., a corporation of Connecticut

Application October 18, 1939, Serial No. 299,943

8 Claims. (Cl. 158—91)

The present invention relates to liquid fuel burners, and is more particularly directed toward power operated pot type oil burners.

The present invention contemplates power operated pot type oil burners designed for inexpensive manufacture, ease of assembly and of disassembly, so that the parts may be cleaned and/or replaced as occasion requires with a minimum of difficulty.

According to the present invention the burner has an outer casing which may be suitably fixed in the fire box, and this casing is adapted to receive from the top a unitary assemblage of supporting ring, fuel receiving trough, perforated cylinder, and central air distributor. This unit may also include a baffle plate below the trough and above the blower.

The invention also contemplates in the preferred form of construction that the blower including electric motor and impeller fan will be in the form of a complete preassembled unit which is secured to the casing so as to be downwardly removable.

Certain features shown herein and relating to flame propagation and air distribution are shown and claimed in my copending application Serial No. 377,613 filed February 6, 1941.

Other and further objects will appear as the description proceeds.

The accompanying drawings show, for purposes of illustrating the present invention, several of the many embodiments in which the invention may take form, it being understood that the drawings are illustrative of the invention rather than limiting the same.

In these drawings:

Figure 1 is a vertical sectional view through a power operated pot type burner;

Figure 1a is a fragmentary view of a detail on line 1a—1a of Figure 1;

Figure 2 is a fragmentary sectional view of the structure of Figure 1 showing in addition, a baffle;

Figures 3, 4 and 5 are vertical sectional views through modified forms of burner;

Figure 6 is a top plan view of the form of construction of Figure 5, with parts broken away;

Figure 7 is a diagrammatic view illustrating the shape of the flame;

Figure 8 illustrates a modified form of outer deflector ring;

Figure 9 is a vertical sectional view through a modification of the structure of Figure 5; and

Figure 10 is a top plan view of the vaporizer of Figure 9.

In the arrangement shown in Figures 1 and 2 the burner is shown as being supported from a ring 10 or other suitable support in the fire box. These supports receive a burner supporting ring 11 which may be secured to the burner in any convenient manner, as, for example, by the screws indicated at 12.

The burner has an outer sheet metal casing 13, here shown as including a cylindrical member 13a and a shallow stamping 13b, these parts being spot welded at 13c. A ring 14 rests on top of the casing 13 and may be held in place by screws indicated at 15. Bolts 16 extend down through the ring 14 as indicated, and support the internal parts to be described. These bolts pass through the flange 17 of a stamping or casting 18 shaped to provide an annular fuel receiving trough 19 and act as a vaporizer. This trough is stepped as indicated at 20, and a sheet metal cylinder 21 is fitted between stamping 18 and the ring 14 as will be obvious, the joints (where a sheet metal trough is used) being sealed by black asbestos cement as indicated at 21a. The cylinder 21 is provided with comparatively large widely spaced holes 21' in its upper part and smaller more closely spaced holes 21'' in its lower part. A vapor baffle 30 (shown in Figure 2) may be placed in the bottom of the trough 19.

The bolts 16 extend down through spacers 22 and through a baffle plate 23. Nuts 24 on the bolts 16 secure the baffle plate and spacers, trough, perforated member and ring together. The baffle plate 23 carries a number of downwardly depending fins 25. The upper inner edge 18' of the trough supports a central air distributor 26 preferably made of cast iron and having holes as indicated at 27, 28, and an upper flame spreader stamping indicated at 29.

40 The vaporizer 18 is connected to a coupling member or bushing 31 placed opposite an opening 32 in the casing so as to receive a cooperative coupling member 33. A tube 34 passes through a hole in the flange 17 and is threaded into the coupling 31 to provide an air supply in the inlet passage.

45 The bottom stamping 13b of the casing is provided with a comparatively large bottom opening slotted and offset, as indicated at 36, to form part of a bayonet joint connection. The stamping 13b also carries three posts 37. These posts receive springs 38 which press downwardly on a pressure plate or cup 39 whose peripheral portion 40 is curved and brought adjacent the outer part of the casing to direct the air stream

up and reduce air leakage. This pressure plate has a central opening indicated at 41.

An electric motor 42 is secured to the lower face of a mounting plate 43, which has a central opening 44. The shaft 45 for the motor extends through this opening and carries an impeller or blower 46. The plate 43 has outwardly extending lugs 47 adapted to enter the slots 36 after the fashion of a bayonet joint so as to lock the plate and parts carried thereby in place, the pressure plate acting to hold them securely. The plate 43 has downwardly bent projections 48 to receive a cup shaped cover member 49 having an air inlet opening 50 and carrying the wiring connections 51. Various other forms of motor, fan and housing assemblies can be used.

When the parts are assembled, as shown in Figures 1 and 2, oil will be admitted through the fuel supply line and run into the trough at the rate determined by the metering valve in the fuel supply line. Air will be drawn in by the motor operated fan or blower and distributed about the periphery of the baffle plate 23 to build up a positive pressure above the baffle plate, this pressure being substantially uniform throughout. Some of the air will pass up by the edge of the flange 17 of the trough forming stamping, and this air will be forced inwardly through the openings 21' and 21" in the cylinder 21. Some of the air passes up into the central air distributor and through the holes 27 and 28 as indicated. The lower openings 21" and 21' will cause flame to play on the fuel surface and vaporizing bottom so as to maintain combustion at a low level and consume residues. The air blown out through the upper holes 21' and 28 engages the rising flame and assists in burning the fuel gases. In the form here shown the flame spreader 29 directs the flame out to produce a wide flat flame suitable for use in certain forms of apparatus.

The flame spreader, as well as the central air distributor 26, and the loose upper ring 52 may be readily removed. When the screws 15 and the coupling 33 are removed, all the upper parts of the device can be readily lifted up, inspected, repaired, if necessary, and then replaced. The entire motor blower unit can also be removed complete and replaced whenever necessary.

The arrangement shown in Figure 3 is similar to that shown in Figure 1, except that the perforated cylinder 211 is shorter and the step 201 where it fits the stamping 18' is higher, and a different form of central air distributor 26' and flame spreader 29' is employed.

In the arrangement shown in Figure 4 the entire casing 60 is a single sheet metal stamping. The ring 61 is a stamping adapted to fit the top of the stamping 60. The trough forming stamping 62 is secured to the ring 61 by bolts and spacers indicated at 63 and 64. The baffle plate 65 is secured to the stamping 62 by bolts and spacers 66 and 67. The central cylinder 68 is of slightly different construction and has openings 69 at the top below the flame spreader 69'. The motor 70 is secured to a plate 71 which in turn is secured to the stamping 60. The fan 72 is secured to the motor shaft 73 before the upper assemblage is lowered down into the casing 60.

In the construction shown in Figures 5 and 6 the burner is supported from underneath by a ring 80. The burner has an outer sheet metal casing 81 formed of two stampings in a manner similar to that shown in Figure 1. A bottom

plate 82 is secured to the support 80 by bolts 83 and its level is adjusted by screws 84. The bottom casing part 82 supports a blower motor and fan which may be the same as that shown in Figure 1, and for convenience the same reference characters are applied. The upper casing part 81 supports a ring 85 similar to the ring 14, and this ring is assembled with a perforated cylinder 86, an annular fuel receiving trough 87, bolts 108, spacers 89, and a baffle plate 90 in the same manner as above described.

Vaporizing trough 87 is here shown in the form of a casting and is provided with a well 91 slightly below the general level of the trough and adapted to receive fuel required for the low flame. A small asbestos pad 92 is placed in this well. The vaporizer casting 87 is connected to a fuel supply line comprising a nipple 93, a Y-connection 94 and a pipe line 95 leading to the constant level valve. The Y-coupling 94 is connected to a tube 96 which extends through an opening in the outer casing wall 81. The inner wall 87' of the trough supports the central air distributor which is here shown in the form of two annular elements 97, 98 and a cap 99. The element 97 has holes, indicated at 100, for directing air downwardly across the fuel receiving trough and holes 101 for directing the air upwardly. The cap 99 is spaced from the upper end of the member 98 to provide an air passage 102 as indicated. The ring 85 supports a ring 103 which extends over close to the outer edge of the cap 99 and also downwardly opposite the perforations in the upper part of the member 35 of the cylinder 86.

In its general mode of operation the device of Figures 5 and 6 is the same as that of Figure 1. It, however, has certain additional features which will now be mentioned. Oil flows in to the well 91 and wets the asbestos pad so that it is easy to start the burner into operation. After the burner has been operated for some time the presence of the asbestos pad is of little importance as it becomes easier to ignite the fuel in a burner which has been operated previously. In order to sweep away any carbon or other deposit when the burner is operating, air is passing through the tube 96 and enters through the well 91 to produce an oxidizing flame. Should any carbon form while the pilot flame is burning it will be consumed and eliminated when the burner goes to high flame.

By having the ring 103 extend down opposite the upper part of the perforated cylinder, fresh air is projected downwardly and inwardly, as shown by the arrow at the left of Figure 5. This air is very hot because of the high temperature of the ring 103. The air which blows through the openings 102 is directed downwardly and outwardly and is also very hot on account of the high temperature of the cap 99. This hot air blowing down into the combustion zone thoroughly agitates the flame and brings fresh air into contact with any unconsumed gases so that there is little likelihood of smoke or soot formation. With the arrangement shown in Figure 5 the flame is confined in a narrow comparatively high region above the burner, as indicated in Figure 7.

Where it is desired to have the flame spread more widely, as, for example, while using the burner under hot water heaters or in cook-stoves, one could use a ring 103' such as shown in Figure 8.

In the arrangement shown in Figure 9 the

burner is generally the same as that shown in Figure 5 and corresponding reference characters are used for the same parts. The vaporizer 105 is a casting supported the same way as the vaporizer 87 of Figure 5 and it supports the central air distributor 98' as before. The perforated cylinder 106 is shorter than the cylinder 86 and engages the top flange 107 of the vaporizer 105. The vaporizer has an oil receiving well 108 provided with fins 108' to form sockets for pads 108'' of asbestos or rock wool. It is supplied with oil from a pipe 109 into which air is introduced by a centrally disposed tube 110. This well holds oil for the pilot flame and when more oil is supplied it overflows into the trough formed by the vaporizer casting 105. The inner portion 111 of the trough has a small radius of curvature in vertical planes so that only a small quantity of oil is required to form a pool all the way around the riser 112. The bottom of the vaporizer beyond this portion is substantially conical as indicated at 113 to form a large area for the pool of oil beyond this the surface sweeps upwardly and outwardly in a gentle curve as indicated at 114. At the outer edge of the pool of oil the oil depth is so small that there is no substantial mass of oil to provide residues.

The air passes down through the holes 100 and sweeps across the top of the pool of oil. Combustion starts over the inner part of the oil pool and continues as the air radiates outwardly. By the time it has reached the edge of the pool it is hot enough to vaporize all the oil and the oil vapors and air sweep up past the holes in the cylinder 106 where more air is supplied.

The arrangement just described has been found to be of particular advantage in the larger sized burners in that there is a minimum formation of residues after long operation of the burner. The residues normally experienced in burning No. 2 fuel oil in pot type burners is minimized in this construction, as the residues appear to be swept off the bottom of the well and consumed by the air currents sweeping over the surfaces. In the larger sized burners the ring 103 of Figure 5 is sometimes omitted, as indicated in Figure 9. This facilitates the radiation of heat from the flame above the burner down into the vaporizer.

While the drawings herein show complete units wherein the fuel consuming and air distributing parts are combined with a blower, it is obvious that a remote source of forced draft may be employed.

It is obvious that the invention may be embodied in many forms and constructions within the scope of the claims and I wish it to be understood that the particular forms shown are but a few of the many forms. Various modifications and changes being possible, I do not otherwise limit myself in any way with respect thereto.

What is claimed is:

1. In a liquid fuel burner, a cup shaped casing having a bottom opening of substantially smaller diameter than the casing, an annular ring supported on the top of the casing, an annular fuel receiving trough disposed below the ring, a perforated cylinder spaced from the casing wall and extending between the trough and the ring, a baffle plate disposed within the casing below the trough, a central air distributor supported on the trough, and means coupling the trough, the plate,

and ring together so that they with the cylinder and distributor can be removed or replaced as a unit.

2. A liquid fuel burner such as claimed in claim 1, having a motorized blower unit detachably secured to the casing below the baffle plate.

3. In a liquid fuel burner, an outer casing having a wide flange at the bottom to provide a small opening, an electric motor below the casing, a blower above the opening for drawing air in through the opening and discharging it radially, a ring secured to the top of the casing, an annular fuel receiving trough supported from the ring, an annular perforated wall inside the casing and extending from the ring to the trough and through which a part of the air for combustion passes, a fuel supply inlet leading to the trough, a central air distributor supported from the oil receiving trough, and extending up through the opening in the ring, and a horizontal fixedly secured plate below the trough and above the blower and flange, the plate having its edge spaced from the casing wall and having downwardly extending radial fins spaced uniformly about the periphery of the plate whereby the air is blown outwardly against the casing walls so as to pass upwardly along said walls and inwardly under the trough to feed air to the central air distributor.

4. A liquid fuel burner as in claim 3, wherein the motor and blower are in the form of a unit detachably connected to the casing, the blower being smaller than the bottom opening of the casing so that it may be removed downwardly.

5. In combination, a pot type liquid fuel burner having an outer casing with a bottom opening substantially smaller than the diameter of the casing, an electric motor external of the casing, a motor operated blade-type blower in the casing above the opening and of less diameter than the opening so that it can be passed therethrough whereby the unit comprising the motor and blower may be detached as a unit for inspection or replacement, and a fixed baffle plate above the blower and having its edge spaced from the casing wall, and downwardly extending radial fins which distribute the air about the periphery of the plate.

6. In combination in a pot type liquid fuel burner having an outer casing with a notched bottom opening substantially smaller than the diameter of the casing, an apertured closure plate having a bayonet slot connection with the notched casing opening, a motor secured to the lower side of the plate, a blower on the motor shaft above the closure plate and adapted to pass through the opening in the casing whereby the unit comprising the motor and blower may be detached as a unit for inspection or replacement, and a fixed baffle plate above the blower and spaced from the casing wall to permit air to pass upwardly, and downwardly extending radial fins which distribute the air about the periphery of the plate.

7. The combination of claim 6, having a spring actuated pressure plate for holding the closure plate in position.

8. The combination of claim 6, having a spring actuated presser plate for holding the closure plate in position, the periphery of the presser plate extending out adjacent the chamber walls to direct air upwardly.

RALPH W. DE LANCEY.
